UNITED STATES PATENT OFFICE

HUGO SCHNEEBELI, OF COURBEVOIE, FRANCE

CARBURETOR

Application filed October 29, 1931, Serial No. 571,900, and in France November 7, 1930.

This invention has for object a carburetor for internal combustion engines, which is so constructed that it does not comprise a constant level tank and is directly supplied with 5 gasoline by the gasoline tank which is under pressure or under partial vacuum.

This carburetor is essentially characterized by the combination:

1.—Of an atomizing chamber in constant 10 communication with the atmosphere through a cylinder perforated with orifices and a primary air inlet tube, this chamber being so arranged that it can be put in communication with the gasoline intake through a double obturator constituted by a needle valve 15 controlling the flow of gasoline into the said chamber and adjustably mounted in a sheath which, connected through a suitable transmission to a control lever actuated by the 20 driver, is longitudinally movable with the control needle valve and is adapted to close, when the carburetor is at rest, the admission of gasoline in the atomizing chamber;

2.—Of a tube connected to the said chamber and so arranged as to transmit in the latter the partial vacuum produced by the engine and to carry, into the suction connecting branch of the engine, the rich emulsion formed in the said atomizing chamber, this 25 tube having orifices open to the atmosphere and so arranged as to mix fresh quantities of primary air with the emulsion circulating in the said tube;

3.—Of a device interposed between this 30 tube and the engine for intimately mixing, in adjustable quantities, the emulsion drawn into the said tube with secondary air and to deliver the homogeneous explosive mixture thus obtained into the suction connecting 35 branch of the engine, this device comprising, within a chamber of the carburetor body which is directly connected to the suction pipe of the engine pierced with secondary air inlet ports:

(a) A fixed sleeve having two superposed 40 annular grooves putting the interior of the said sleeve in communication with the emulsion supply tube, through suitable orifices;

(b) A sheath sliding in the said chamber 45 of the carburetor body and in the above fixed

sleeve, and so arranged as to be lowered by a spring for partly closing the secondary air inlet ports when the engine is at rest, and to be lifted upon each suction cycle of the said engine, by the partial vacuum produced in 55 the suction connecting branch, for uncovering the secondary air inlet ports and allowing the admission of this secondary air in the fixed sleeve and its mixing with the explosive gas delivered into the said sleeve; 60

(c) An obturator movable within this sliding sheath for closing the latter to a greater or less extent and controlling the admission of secondary air, this obturator being connected, by a suitable transmission, to the 65 sheath controlling the admission of gasoline into the atomizing chamber, so as to ensure the simultaneousness of the control of the admission of gasoline and primary air and of the control of the admission of secondary air. 70

The invention is moreover characterized by the following points:

(a) The double obturator controlling the admission of gasoline is so arranged that it can be controlled independently of the obturator controlling the admission of secondary air; 75

(b) The obturator controlling the admission of secondary air is provided with a piston, moving with some play in the primary 80 air inlet cylinder, in order to balance the effect exerted, on the said obturator, by the partial vacuum of the engine and to render the control smoother;

(c) The sprayer is constituted by a tube 85 which, having an inner partition perforated, for the passage of the gasoline, with a central hole, of adjustable section, for the needle valve, is so shaped, at the end opening in the vaporizing chamber, as to constitute a seat 90 against which the sheath is pressed under the action of a spring for closing the spraying nozzle;

(d) The tube constituting the spraying 95 nozzle is provided, on its outer face, with longitudinal grooves and fits in a circular bore of the sleeve, secured in the carburetor body and in which the double obturator is mounted; this spraying nozzle is removably secured in its housing by means of a nut 100

which ensures, at the same time, the locking of the union connecting the spraying nozzle to the gasoline tank, and is perforated with orifices so arranged as to put the atomizing 5 chamber in communication with the atmosphere through the medium of the grooves of the spraying nozzle and to allow, during the suction periods, the admission of primary air in the said chamber, simultaneously with the 10 admission of gasoline supplied by the central orifice of the spraying nozzle;

(e) The sheath controlling the opening and closing of the spraying nozzle is so mounted as to longitudinally slide in the sleeve carrying 15 this spraying nozzle and is provided, for that purpose, with an outer flange held in contact with a nut which, journalled on the said sleeve and controlled by the driver by means of a suitable transmission, drives the obturating sheath through the medium of its flange and moves it towards or from the seat of the spraying nozzle;

(f) The needle valve controlling the section of the orifice of the spraying nozzle is frictionally mounted within the obturating sheath, and projects outside the latter in the form of a screw-threaded rod provided with a nut and a lock-nut, resiliently held in contact with the flange of the obturating sheath 30 and so arranged as to constitute abutments ensuring the actuation of the needle valve by the said sheath when the latter is moved to opening position, and allowing, by a rotation imparted in a suitable direction to the said 35 needle valve, to modify its position within the obturating sheath and to control the initial cross section of the orifice of the spraying nozzle as well as the outflow of the latter;

(a) The connection of the needle valve and 40 of the obturating sheath is ensured by a spring so arranged as to act on the end of a lever, and interposed between the nut and the lock-nut of the needle valve, and to hold the flange of the obturating sheath clamped between 45 the nut of the needle valve and the nut controlling the simultaneous displacements of the said sheath and of the said needle valve, whilst allowing to adjust the position of the latter.

50 A form of construction forming the subject-matter of the invention will be described hereinafter with reference to the accompanying drawings in which:

Fig. 1 is an elevation;
55 Fig. 2 is a partial vertical longitudinal section made according to line A—A of Fig. 3;

Fig. 3 is a horizontal section made according to line B—B of Fig. 2.
60 Fig. 4 is a vertical cross section made according to line C—C of Fig. 2.

Fig. 5 is a partial vertical section of another form of construction of the spraying nozzle and of the double obturator.

65 As illustrated in the accompanying draw-

ings, the improved carburetor comprises a tubular body 1, Fig. 3, which is connected to the gasoline tank or to the exhauster, by means of a union 2 screwed on one of its ends, and of a suitable connection.

This body 1 contains a nozzle 3 perforated with a gasoline inlet channel 4, the cross section of which, for controlling the outflow, can be regulated at will by means of a needle valve 5 which, screwing in a sheath 6 sliding in the body 1, can be rotated by hand in the said sheath through an operating knob 7, and held stationary in any adjusted position by means of a locking member 8 entering one of the notches 9 formed in the head of a nut 10 which is screwed on a screw-threaded part 11 of the tubular body 1 and is connected, by a key 12, to the sliding sheath or tube 6.

This sheath 6 terminates, on the side of the gasoline inlet nozzle 3, in a conical part 13 acting as a valve and so arranged that when the carburetor is idle, it can fit against a conical seat 14 of the said nozzle for closing the gasoline intake in a fluid-tight manner, and, when the carburetor is in action, it can be moved away from the said seat, as illustrated in Fig. 2, for allowing the admission of gasoline.

The tube 6 bears against the nut 10, through a flange 15 resiliently pressed against the said nut by means of a spring 16 acting on a lever 17 terminating in a fork 18 pivoted at 19 and between the branches of which the needle valve 5 is retained by its knob 7.

By means of this arrangement, it is possible, when the valve 13 is pressed upon its seat 14, upon stoppage of the engine, to start the latter by a sudden unseating of the valve 13 by pushing back the lever 17 in opposition to the action of its spring 16.

During working, the degree of opening of the valve 13 is adjusted as explained herein-after, by angularly moving the nut 10 which through the key 11, actuates the unit constituted by the sheath 6 and the needle valve 5.

In fact, this needle valve 5 follows the movements imparted to the sheath 6, the valve 13 of which controls the admission of gasoline or stops the supply of gasoline, but it is to be noted that the position of the said needle valve in this sheath 6, for an outflow adjusted by the latter, is not modified by the displacements imparted to the said sheath 6 and that, when the latter closes, by its valve 13, the gasoline inlet, the needle valve 5 never comes in contact with the orifice of the channel 4, so that there is no risk of this orifice being damaged and that the control of the outflow by the said needle valve can, from this fact, be perfectly ensured.

When the valve 13 is open, the gasoline supplied through the channel 4 flows into a circular groove 20, provided within the tubular body 1 and in constant communication,

through a series of channels 21, with an annular chamber 22 bounded by a circular bore 23 formed in the outer face of the tubular body and by the inner wall of a circular bore 24 formed in the body 25 of the carburetor and in which is rigidly secured the tubular body 1 enclosing the double obturator 5—6.

At two diametrically opposite points of the chamber 22 open two channels 26 and 27 communicating together through a circular groove 28 provided in the sheath 6 and putting the said chamber in communication with the atmosphere through the medium of a tube 29, connected to the body 1 in alignment with the channel 27 and on the bottom of a cylinder 30 perforated, at its upper part, with orifices 31 open to the atmosphere and serving to admit primary air into the chamber 22.

20 A conduit 32, arranged in the body of the carburetor 25 which is connected, by its flange 33, to the suction connecting branch of the engine, puts moreover the chamber 22 in communication with the said suction connecting branch, so that the partial vacuum produced by the engine is transmitted to the said chamber 22, and through the channels 26 and 27 and the tube 29, to the cylinder 30, and that the gasoline delivered in the groove 20 is carried in a divided condition, through the channel 21, into the chamber 22, at the same time as the primary air, admitted through the orifices 31 under the action of this partial vacuum, enters the said chamber and intimately mixes with the gasoline by pulverizing the latter and forming a very rich emulsion.

Referring to Fig. 4, it will be seen that the body 25 is provided, at the place where it is connected to the suction connecting branch 40 of the engine, with a chamber 33, of circular cross section, communicating, at its lower part, with the atmosphere through ports 34 and having, at its upper part, two orifices 35 and 36 opening at the top of the tube 32 opposite two conical channels 37 and 38 perforated in plugs 39 and 40 open to the atmosphere through a flared orifice; a third plug 41, secured in the body 25 and perforated with a flared channel 42, puts the lower part of the tube 32 in communication with the atmosphere.

In the chamber 33 is rigidly secured a sleeve 43 so shaped as to open in the suction connecting branch of the engine through the 55 opening of larger diameter of a conical bore 44, this sleeve 43 having a cylindrical bore 45 on the remainder of its length.

Externally, this sleeve 43 is provided with two circular grooves 46 and 47 forming, with 60 the inner wall of the chamber 33, two superposed annular chambers respectively arranged opposite the orifices 35 and 36 and perforated, opposite the latter, with holes 48 and 49 putting the said chamber in communication with the interior of the sleeve 43. This

sleeve 43 is moreover perforated with two circular rows of orifices 50 and 51 also putting these chambers 46 and 47 in communication with the interior of the sleeve 43.

In the chamber 33 is also mounted a sheath 52 having a cylindroconical inner bore terminating, at its lower part, in a flared opening. This sheath 52 is so arranged that it can move vertically downwards under the action of a spring 53, and upwards in opposition to the action of this spring, under the effect of the partial vacuum produced by the engine.

In its lowest position, corresponding to stoppage of the engine, this sheath 52 rests on a fibre washer 54, fitted in a groove of the body 25, and is thus placed opposite the additional air inlet ports 34.

In its uppermost position, this sheath uncovers these ports 34 and, through an orifice 55, puts the groove 47 of the fixed sleeve 43 in communication with the suction connecting branch of the engine, through the medium of the said sheath and of the sleeve 43.

Within the movable sheath 52 is mounted an obturator 56, which can be vertically moved in the said sheath and adapted to modify, according to requirements, the inner cross section of this sheath and to thus control the admission in the latter of secondary air drawn in, through the ports 34, by the partial vacuum produced by the engine.

This obturator 56, which is subjected, on its upper face, to the action of the partial vacuum produced by the engine, as will be explained hereinafter, is secured to the upper end of a rod 57 suitably guided in the carburetor body and provided, at its lower end, with a washer 58 mounted with some play in the primary air inlet cylinder 30 and adapted to counterbalance the action of partial vacuum on the head of the obturator 56 and to facilitate the operation of the latter.

The rod 57 of this obturator carries, moreover, a rack 59 gearing with a toothed segment 60, rigidly secured on a shaft 61 journalled in the body 25.

On this shaft 61 is rigidly secured a two-arm lever 62—63, to both arms of which are respectively connected two links 64 and 65. The first of these links is connected, on the one hand, to the crank pin of a crank 66 rigidly secured on the nut 10, whilst the second link 65 is connected, through the medium of a second two-arm lever 67 and 68 pivoted at 69 on the carburetor body, to a control link 70 so arranged as to be actuated by the driver and to allow the latter, by simultaneous angular movements imparted to the nut 10 and to the toothed segment 60, to obtain the simultaneousness of control of the sheath 6 and of the obturator 56, and, consequently, to control the admission of gasoline and primary air in the atomiz- 130

ing chamber 22 and the admission of additional air in the sliding sheath 52 and the fixed sleeve 43 connected to the suction connecting branch of the engine.

5 When the engine stops, the valve 13 closes the gasoline inlet, and the obturator 56 is lowered and covered by the sliding sheath 52 which bears, under the action of its spring 53, on the fibre washer 54.

10 As the valve 13, rigid with the sliding sheath 6, has been opened by a thrust exerted on the link 70, it will be understood that gasoline enters the groove 20, and that the obturator 56, which is moved simultaneous-

15 ly with the sheath 6, is introduced in the movable sheath 52 and closes the latter to a greater or less extent. The vacuum produced by the engine upon starting, is transmitted in the pulverizing chamber 22

20 through the sleeve 44, sheath 52 and the orifices 48—49 and 35—36. Under these conditions, it is evident, that the vacuum produced by the engine causes the lifting of the movable sheath 52 and the simultaneous

25 suction in the chamber 22 of the gasoline supplied through 4 and of primary air which is drawn into the said chamber through the tube or conduit 29 and the cylinder 30 in communication with the atmosphere through

30 the orifices 31.

This partial vacuum causes the lifting of the sheath 52 and the suction, in the chamber 22, of the gasoline distributed by the channel 4 and, at the same time, a primary 35 air draught which enters the cylinder 30, through the orifices 31, and is admitted in the chamber 22, through the tube 29, channel 27, groove 28 and channel 26.

The gasoline, divided by its passage in the 40 channels 21, is emulsified with primary air admitted into the chamber 22, as just explained, and the very rich emulsion thus formed is carried out from the said chamber through the conduit 32.

45 When entering the latter, this emulsion receives a further quantity of primary air which enters the said tube 32, through the nozzle 42, and intimately mixes with the said emulsion during its upward movement in

50 this tube 32.

When issuing from this tube, the gaseous mixture thus formed is drawn towards the suction conduit of the engine, and passes through the openings 36 and 35, carrying 55 along with it further quantities of primary air which is admitted through the channels 38 and 37 of the plugs 40 and 39.

This gaseous mixture, under the action of the partial vacuum of the engine, circulates 60 in both chambers 46 and 47, from which it escapes through the series of orifices 49—48 and 50—51 for entering, in a divided condition, the sliding sheath 52 and the fixed sleeve 43. Within this sheath 52 and sleeve 43, the 65 said gaseous mixture is brought in contact

and intimately mixed, before its admission in the suction connecting branch of the engine, with secondary air drawn into the said sheath 52 and into the sleeve 43, this secondary air entering these latter through openings 34 and the annular interval comprised between the sheath 52 and the obturator 56, and the adjustable section of which is determined by the position given to this obturator 56 in the sheath 52, which latter is lifted, as above explained, by the partial vacuum produced by the engine and uncovers the secondary air inlet openings 34, as shown in Fig. 4.

70 For ensuring the freedom of movement of the sheath 52, the annular chamber, in which is enclosed the spring 53, is in constant communication, through orifices 71, with the interior of the said sheath, in order to obtain equality of the pressure within this sheath and within the chamber of the spring.

75 Moreover, an annular channel 72 is provided in the body 25 and adapted to allow the circulation of the exhaust gases about a jacket 73 in which the sheath 52 slides, and to thus avoid, in cold weather, the formation of frost about the said sheath and the wedging of the latter.

80 Referring to the form of construction illustrated in Fig. 5, it will be seen that the spraying nozzle is constituted by a tube 3 provided with an inner partition, at the centre of which is formed the orifice 4 of the spraying nozzle.

85 This spraying nozzle, which is introduced in a bore of the body 1, is externally fluted or provided with grooves extending throughout its length and forming, with the inner wall of the housing receiving the spraying nozzle, a series of longitudinal channels 3^a.

90 The spraying nozzle is held in position in its housing by means of a nut 80 which is 105 screwed on the body 1 and locks, at the same time the union 2 putting the spraying nozzle in communication with the gasoline tank through the medium of a suitable pipe line.

95 This nut is perforated with orifices 81 putting the atomizing chamber 22, formed about the body 1, in communication with the atmosphere, through the channels 3^a, as explained with reference to Figs. 1 to 4.

100 The spraying nozzle 3 opens, at its inner end, in the groove 20 which is formed within the body 1 and is adapted to simultaneously receive the gasoline delivered by the orifice 4 of the spraying nozzle and the primary air drawn in, during the suction periods of the engine, through the orifices 81 of the nut 80 and entering the said groove 20, through the channels 3^a.

105 The rich mixture formed in this groove 20 is drawn into the atomizing chamber 22, through the orifices 21, perforated in the body 1, between the said groove and this chamber 22.

110 The section of the orifice 4 of the spraying nozzle is controlled, as above indicated with

reference to Figs. 1 to 4, by a needle valve 5 which is mounted in the sheath 6 terminating, on the side of the spraying nozzle, in a conical part 13 acting as a valve, and adapted upon 5 stoppage, to fit against a seat 14 provided at the inner end of the spraying nozzle, and to close the latter in an absolutely fluidtight manner.

This sheath 6 is mounted in the body 1 so 10 as to be slidable in the latter, and it is provided, opposite the atomizing chamber 22, with a circular groove 28 putting the said chamber in communication with the groove 20, in which the gasoline, and the primary 15 air, are simultaneously admitted, during the suction periods, respectively through the orifice 4 of the spraying nozzle, and through the channels 3^a of this spraying nozzle.

At its outer end, this sheath 6 is provided 20 with a flange 15 resiliently pressed against a nut 10 which is screwed on a screw-threaded portion of the body 1 and can be angularly moved on the latter through the medium of a crank 66, rigid with the said nut 10, and 25 of a suitable transmission, for causing the rectilinear displacement of the sheath 6 and the opening of the spraying nozzle by unseating the valve 13 rigid with the said sheath, as above explained.

30 In the form of construction illustrated in Fig. 5, the needle valve 5 controlling the output of the spraying nozzle is so mounted that it can slide in the sheath 6, outside which it projects in the form of a screw-threaded rod 5^a on which a nut 82 and a lock-nut 83 are screwed.

Between the nut 82 and the lock-nut 83 is 40 arranged a lever 84 pivoted at 85 on an arm 86 rigidly secured on the carburetor and about which is wound a spring 87 bearing, on the one hand, against the carburetor, and, on the other hand, against a socket 88, provided with a finger 89 engaging with the free 45 end of the lever 84.

By means of this arrangement, the spring 87, through the medium of the lever 84, pushes the needle valve 5 towards the spraying nozzle, and, consequently, tends to insert 50 the said needle valve in the orifice 4 of the spraying nozzle.

The said spring 86 holds the flange 15 of the sheath 6 between the nut 82 of the needle valve and the nut 10 controlling the rectilinear movements of the obturator-sheath 6.

In these conditions, the angular movements imparted to the nut 10 have for effect to simultaneously actuate the obturator-sheath 6 and the needle valve 5, and to close or open 60 the spraying nozzle, according to the direction of the movement imparted to the said nut 10.

The initial adjustment of the gasoline outflow through the orifice 4 of the spraying nozzle is effected by displacing the needle

valve 5 within the sheath 6. This displacement is obtained by causing the screw-threaded rod 5^a, rigid with the needle valve 5, to rotate in the nut 82, and by locking the needle valve 5 in the desired position by 70 means of the lock-nut 83; for that purpose, the rod 5^a is provided, at its end, with a groove adapted to receive a screw driver.

It will be understood that this adjustment 75 can be easily and accurately effected during working or during the trials of the carburetor.

It will also be seen that the form of construction above described is more simple than that illustrated in Figs. 1 to 4, and, moreover, that it allows the very easy and rapid removal of the spraying nozzle and of the double obturator 5—6, as well as a perfect control of the carburation.

I claim:

1. A carburetor for internal combustion engines, comprising: a carburetor body, a tubular sleeve secured in a bore of the said body, a union secured on said sleeve and putting the sleeve in direct communication with the gasoline tank, without interposition of a constant lever chamber, a nozzle adapted to constitute a sprayer, in said sleeve, and perforated with a channel for the admission of gasoline, a conical seat surrounding the outlet orifice of the said channel, means for controlling the closing, opening and output of the spraying nozzle, an annular chamber formed in the tubular sleeve, about the conical seat of the spraying nozzle, and adapted to receive gasoline delivered by the spraying nozzle, a circular groove, provided in the outer wall of the tubular sleeve and adapted to form with the shape of the carburetor body, a gasoline atomizing chamber, channels putting the atomizing chamber in communication with said annular chamber, means for putting the atomizing chamber in communication with the atmosphere for the admission of primary air, its mixing with the gasoline admitted in the said chamber, and the atomization of the gasoline in the form of a rich emulsion, means for transmitting in this atomizing chamber the partial vacuum produced by the engine and supplying the emulsion produced in the said chamber to the suction connecting branch of the engine, means for adding to and mixing with this emulsion further quantities of primary air during its passage from the atomizing chamber to the suction connecting branch of the engine, means for controlling the admission of this mixture into the suction connecting branch of the engine, means for ensuring the introduction in this mixture of adjustable quantities of secondary air and for delivering this explosive mixture in the suction connecting branch of the engine, and means adapted to ensure the simultaneousness of the control of the admission of gaso-

line and primary air and of the control of the admission of secondary air.

2. A carburetor for internal combustion engines, comprising: a carburetor body, a tubular sleeve secured in a bore of the said body, a union secured on the sleeve and putting the latter in direct communication with the gasoline tank, without interposition of a constant level chamber, a nozzle adapted to constitute a sprayer, mounted, in the sleeve, and perforated with a channel for the admission of gasoline, a conical seat surrounding the outlet orifice of the said channel, a sheath sliding in the tubular sleeve and adapted, upon stoppage of the carburetor, to fit upon the said conical seat for closing the spraying nozzle, a needle valve mounted in this sheath, moving with the same, and adapted to come opposite the outlet orifice of the spraying nozzle and to control the output of the latter, means for adjusting the position of the needle valve in the sheath which carries it, means for controlling the displacements of the double obturator constituted by the said sheath and the needle valve, an annular chamber formed in the tubular sleeve, about the conical seat of the spraying nozzle, and adapted to receive gasoline delivered by the spraying nozzle, a circular groove, provided in the outer wall of the tubular sleeve and adapted to form with the shape of the carburetor body, a gasoline atomizing chamber, channels putting the atomizing chamber in communication with said annular chamber, a circular groove provided in the outer wall of the sliding sheath, two channels formed in the tubular sleeve, a tube connected to one of these channels and to a cylinder perforated with orifices adapted to put the atomizing chamber in communication with the atmosphere, for the admission of primary air in this chamber, its mixing with gasoline and the formation of a rich emulsion, means for transmitting in this atomizing chamber the partial vacuum produced by the engine and supplying the emulsion produced in the said chamber to the suction connecting branch of the engine, means for adding to and mixing with this emulsion further quantities of primary air during its passage from the atomizing chamber to the suction connecting branch of the engine, means for controlling the admission of this mixture into the suction connecting branch of the engine, means for ensuring the introduction in this mixture of adjustable quantities of secondary air and for delivering this explosive mixture in the suction connecting branch of the engine, and means adapted to ensure the simultaneousness of the control of the admission of gasoline and primary air and of the control of the admission of secondary air.

3. A carburetor for internal combustion engines, comprising: a carburetor body, a tubular sleeve secured in a bore of the said

body, a union secured on the sleeve and putting the latter in direct communication with the gasoline tank, without interposition of a constant level chamber, a nozzle adapted to constitute a sprayer, mounted, in the sleeve, and perforated with a channel for the admission of gasoline, a conical seat surrounding the outlet orifice of the said channel, a sheath sliding in the tubular sleeve and adapted, upon stoppage of the carburetor, to fit upon the said conical seat for closing the spraying nozzle, a needle valve mounted in this sheath, moving with the same, and adapted to come opposite the outlet orifice of the spraying nozzle and to control the output of the latter, means for adjusting the position of the needle valve in the sheath which carries it, means for controlling the displacements of the double obturator constituted by the said sheath and the needle valve, an annular chamber formed in the tubular sleeve, about the conical seat of the spraying nozzle, and adapted to receive gasoline delivered by the spraying nozzle, a circular groove, provided in the outer wall of the tubular sleeve and adapted to form with the shape of the carburetor body, a gasoline atomizing chamber, channels putting the atomizing chamber in communication with said annular chamber, a circular groove provided in the outer wall of the sliding sheath, two channels formed in the tubular sleeve, a tube connected to one of these channels and to a cylinder perforated with orifices adapted to put the atomizing chamber in communication with the atmosphere, for the admission of primary air in this chamber, its mixing with gasoline and the formation of a rich emulsion, a tube connected to the atomizing chamber, adapted to put the latter in communication with the suction connecting branch of the engine and to carry along the emulsion formed in the said chamber, orifices opening in the latter tube and adapted to allow the admission of further quantities of primary air and to ensure the mixing of this air with the emulsion circulating in the said tube, from the atomizing chamber to the suction connecting branch of the engine, another chamber formed in the carburetor body and directly connected to this suction connecting branch, additional air inlet apertures formed in the wall of the last mentioned chamber, another sleeve fixed in the said last mentioned chamber, two annular grooves provided in the fixed sleeve and orifices adapted to put the interior of the said sleeve in communication with the tube carrying the emulsion along, another sheath having a cylindro-conical bore and guided in the last mentioned chamber and in the fixed sleeve and secured in the said chamber, and adapted to be lifted, upon each suction period, by the partial vacuum produced by the engine for uncovering the secondary air inlet apertures and allow-

- ing the admission of this secondary air in the fixed sleeve and in the explosive mixture delivered in the said sleeve, a spring interposed between the fixed sleeve and the last mentioned 5 movable sheath and adapted to lower the said sheath and to partially obturate the additional air inlet apertures upon stoppage of the engine, a movable obturator, housed in the last mentioned sliding sheath and 10 adapted to close the latter to a greater or less extent and to control the admission of secondary air, and means adapted to ensure the simultaneousness of the control of the admission of gasoline and primary air and 15 of the control of the admission of secondary air.
4. A carburetor for internal combustion engines, comprising: a carburetor body, a tubular sleeve secured in a bore of the said 20 body, a union secured on the sleeve and putting the latter in direct communication with the gasoline tank, without interposition of a constant level chamber, a nozzle adapted to constitute a sprayer, mounted, in the tubular 25 sleeve, and perforated with a channel for the admission of gasoline, a conical seat surrounding the outlet orifice of the said channel a sheath adjusted in the tubular sleeve and adapted to fit, upon stoppage of the engine, 30 on the said conical seat for closing the spraying nozzle in a fluid-tight manner, a needle valve having a screwthreaded rod, mounted in this sheath, moving with the latter, and adapted to come opposite the outlet orifice of 35 the spraying nozzle and to control the output of the latter, an outer knob secured to the end of the needle valve and adapted to rotate the needle valve in the sheath, to allow of moving the said needle valve towards or from 40 the orifice of the spraying nozzle, and to vary the section and output of the latter, a nut in engagement with a screw-threaded portion of the carburetor body, a key connecting this nut to the sheath, notches in the said nut and 45 a locking member connecting the needle valve to the said nut, a lever transmission adapted to be actuated by the driver and controlling the rotation of the nut, the displacements of the double obturator constituted by the needle 50 valve and the above sheath and, through the said displacements, the closing, opening and output of the spraying nozzle, a lever, a spring pushing back this lever and holding it against the operating knob of the needle 55 valve for closing the spraying nozzle, an annular chamber formed in the tubular sleeve, about the conical seat of the spraying nozzle, and adapted to receive gasoline delivered by the spraying nozzle, a circular groove, provided in the outer wall of the tubular sleeve and adapted to form with the shape of the carburetor body, a gasoline atomizing chamber, channels putting the atomizing chamber in communication with the annular chamber, 60 a circular groove provided in the outer wall 65 of the sheath, two channels formed in the tubular sleeve, a tube connected to one of these channels and to a cylinder perforated with orifices adapted to put the atomizing chamber in communication with the atmosphere, 70 for the admission of primary air in this chamber, its mixing with gasoline and the formation of a rich emulsion, another tube connected to the atomizing chamber, adapted to put the latter in communication with the suction 75 connecting branch of the engine and to carry the emulsion formed in the said chamber, orifices opening in the last mentioned tube and adapted to allow the admission of further 80 quantities of primary air and to ensure the mixing of this air which the emulsion circulating in the said tube, from the atomizing chamber to the suction connecting branch of the engine, another chamber formed in the carburetor body and directly connected to this suction connecting branch, additional air inlet apertures formed in the wall of the last 85 mentioned chamber, another sleeve fixed in the said chamber, two annular grooves provided in this fixed sleeve and orifices adapted 90 to put the interior of the said sleeve in communication with the last mentioned tube, another sheath having a cylindro-conical bore, and guided in the last mentioned chamber formed in the carburetor body and in the 95 fixed sleeve, and adapted to be lifted, upon each suction period, by the partial vacuum produced by the engine for uncovering the secondary air inlet apertures and allowing the admission of this secondary air in the fixed 100 sleeve and in the explosive mixture delivered in the said sleeve, a spring interposed between the fixed sleeve and the last mentioned movable sheath and adapted to lower the said sheath and to partially obturate the additional 105 air inlet apertures upon stoppage of the engine, a movable obturator, housed in the last mentioned movable sheath and adapted to close the latter to a greater or less extent and to control the admission of secondary air, and means adapted to ensure the simultaneousness of the control of the admission of gasoline and primary air and of the control 110 of the admission of secondary air.
5. A carburetor for internal combustion engines, comprising: a carburetor body, a tubular sleeve secured in a bore of the said body, a union secured on the sleeve and putting the latter in direct communication with the gasoline tank, without interposition of a constant level chamber, a nozzle adapted to constitute a sprayer, mounted, in the sleeve, and perforated with a channel for the admission of gasoline, a conical seat surrounding 120 the outlet orifice of the said channel, a sheath adjusted in the tubular sleeve and adapted to fit, upon stoppage of the engine, on the said conical seat for closing the spraying nozzle in a fluid-tight manner, a needle valve having a screw-threaded rod, mounted in this sheath, 125

moving with the latter, and adapted to come opposite the outlet orifice of the spraying nozzle and to control the output of the latter, an outer knob secured to the end of the needle valve and adapted to rotate the needle valve in the sheath, to allow of moving the said needle valve towards or from the orifice of the spraying nozzle, and to vary the section and output of the latter, a nut in engagement with a screw-threaded portion of the carburetor body, a key connecting this nut to the sheath, notches in the said nut and a locking member connecting the needle valve to the said nut, a lever transmission adapted to be actuated by the driver and controlling the rotation of the nut, the displacements of the double obturator constituted by the needle valve and the above sheath and, through the said displacements, the closing opening and output of the spraying nozzle, a lever, a spring pushing back this lever and holding it against the operating knob of the needle valve for closing the spraying nozzle, an annular chamber formed in the tubular sleeve, about the conical seat of the spraying nozzle, and adapted to receive gasoline delivered by the spraying nozzle, a circular groove provided in the outer wall of the tubular sleeve and adapted to form with the shape of the carburetor body, a gasoline atomizing chamber, channels putting the atomizing chamber in communication with the annular chamber, a circular groove provided in the outer wall of the sheath, two channels formed in the tubular sleeve, a tube connected to one of these channels and to a cylinder perforated with orifices adapted to put the atomizing chamber in communication with the atmosphere, for the admission of primary air in this chamber, its mixing with gasoline and the formation of a rich emulsion, another tube connected to the atomizing chamber, adapted to put the latter in communication with the suction connecting branch of the engine and to carry along the emulsion formed in the said chamber, orifices opening in the last mentioned tube and adapted to allow the admission of further quantities of primary air and to ensure the mixing of this air with the emulsion circulating in the said tube, from the atomizing chamber to the suction connecting branch of the engine, another chamber formed in the carburetor body and directly connected to this suction connecting branch, additional air inlet apertures formed in the wall of the last mentioned chamber, another sleeve fixed in the said chamber, two annular grooves provided in this fixed sleeve and orifices adapted to put the interior of the said sleeve in communication with the last mentioned tube, another sheath having a cylindro-conical bore and guided in the last mentioned chamber and in the fixed sleeve, and adapted to be lifted, upon each suction period, by the partial vacuum pro-

duced by the engine for uncovering the secondary air inlet apertures and allowing the admission of this secondary air in the fixed sleeve and in the explosive mixture delivered in the said sleeve, a spring interposed between the fixed sleeve and the last mentioned movable sheath and adapted to lower the said sheath and to partially obturate the additional air inlet apertures upon stoppage of the engine, a movable obturator, housed in the last mentioned movable sheath and adapted to close the latter to a greater or less extent and to control the admission of secondary air, a rod carrying this obturator and sliding in the carburetor body, a washer secured at the end of the said rod mounted with some play in the primary air inlet cylinder, a rack secured on this rod, a toothed segment meshing with this rack and rigidly secured on a shaft which is adapted to be actuated by the lever transmission actuating the double obturator and thus allow to obtain the simultaneousness of the control of the admission of gasoline and primary air in the atomizing chamber and of the admission of secondary air in the mixture before its introduction in the suction connecting branch of the engine.

The foregoing specification of my "Carburetor" signed by me this 16th day of October 1931.

HUGO SCHNEEBELI.
